UNITED STATES PATENT OFFICE.

HARRY R. NELSON, OF ELIZABETH, NEW JERSEY.

METHOD OF ELECTROLYSIS.

1,149,211.

Specification of Letters Patent. Patented Aug. 10, 1915.

Application filed August 17, 1914. Serial No. 857,088.

To all whom it may concern:

Be it known that I, HARRY R. NELSON, a citizen of the United States of America, residing at Elizabeth, county of Union, State of New Jersey, have invented certain new and useful Improvements in Methods of Electrolysis, of which the following is a description.

This invention relates to an improved method of electrolysis of solutions containing sodium chlorid or other electrolytes.

More specifically my invention has for its object the provision of simple procedure for the electrolysis of electrolytes, such as solutions of sodium chlorid whereby the electrolysis is effected under maximum efficiency, with minimum attention and longest life of the apparatus employed in carrying out my method.

My method is applicable not only to solutions of sodium chlorid and other suitable compounds of sodium, but also to the compounds of the other alkali metals and of the alkali earth metals, etc.

In accordance with my invention, the cathion is set free adjacent a permeable cathode and steam or other like medium is supplied to the cathion in a suitable container inclosing an exterior side of the permeable cathode; the resulting reaction products comprising a liquid or semi-liquid component such as caustic soda and a gaseous component such as hydrogen, are respectively led off to suitable collecting means or directly utilized in other reactions. Such liquid or semi-liquid reaction product is preferably led to a suitable collecting means such as a pan disposed below the cathode and within the container. The gaseous re-

action product is discharged through suitable outlets from the interior of the container. In the preferred forms of the electrolytic cell capable of carrying out my invention, the permeable cathode is a perforated or reticulated cathode bent in a U-shape and disposed in a container surrounding the exterior sides of the permeable cathode. Provision is made for the inflow into the container of the steam or like medium and an outlet for the same, under certain circumstances; also an outlet for the gaseous reaction product. However, otherwise the container is made gastight to conserve the heat of the electrolytic bath and

of the steam, and to preclude the presence 55 of foreign substances, etc. The steam or other like medium is supplied to the cathion in substantially entirely gaseous or vaporous form, and accordingly the supplying means for the steam or like medium is provided 60 with suitable means for trapping the condensed moisture or other liquid to prevent the same from reaching the active reaction area adjacent the cathode. Such condensed moisture or other liquid which may be 65 formed within the container is kept from the reaction area adjacent the cathode and other procedure is pursued to preclude the presence of condensed water or other moisture near the liberated cathion.

The steam or other medium may be supplied to the reaction area adjacent the cathode by solely inlet pipes communicating with the interior of the container, or outlet pipes may also be employed in conjunction with a suitable pump or the like to effect the circulation of the steam from the steam source into and through the container and then return to the steam source under propulsion of the pump or the like. Steam 80 or other like medium is usually supplied to the interior of the container in such amount as to give rise to a "faint cloud," in which case the pressure of the incoming steam or like medium is but little in excess of atmospheric pressure; the evolved hydrogen may be discharged through the outlet pipes for the steam or like medium. It is desirable to provide outlets for the hydrogen on each side of the U-shaped cathode to thereby pre- 85 clude increase in pressure within the container.

To preclude waste of the liquid or semi-liquid reaction product due to "sputtering" caused by the simultaneous evolution of the 95 gaseous product, I prefer to provide within the container and adjacent the exterior side of the cathode a permeable screen of suitable mesh to readily admit the steam therethrough and at the same time to catch the spray of the liquid or semi-liquid reaction product and direct the same to suitable collecting means. The collecting means for the liquid or semi-liquid reaction product is preferably a pan disposed in suitable relation to the cathode and the permeable screen to catch the liquid or semi-liquid reaction product which pan is tilted intermittently 100 105

into a lower pan or other suitable device from which the liquid or semi-liquid reaction product is discharged.

Other features and objects of my invention will be more fully understood from the following description and accompanying drawings, in which—

Figure 1 is a side elevation, partly broken away, of one preferred form of an electrolytic cell, in which my invention may be carried out; and Fig. 2 is a vertical sectional elevation on the line 2—2 of Fig. 1.

Referring more particularly to the drawings, the outer casing member 1 of iron or other suitable metal serves as a support for the electrolytic cell proper and has a chest for the steam or other medium as set forth more fully hereinafter. The cell proper 2 is supported within said casing 1 as by longitudinally extending angle plates 3, 4, the cell proper 2 comprising the diaphragm 5 of asbestos or other suitable material is shown as a sheet curved into a U-shape hung from said oppositely disposed angle plates 3, 4; the cathode member 6 of perforated or reticulated iron or other suitable electrically conducting material is also shown as U shaped and supported by riveting or the like from the positioning angle plates 3, 4. The diaphragm 5 is held in the desired position relative to the centrally disposed anode member 7 by the sides 8, 8, of the dome chlorin chamber 9, of slate or other non-conducting material. The anode member 7 is illustrated as comprising individual anodes carried by the upper wall 10 of the chlorin chamber 9. The diaphragm 5 is preferably secured to the respective angle plates 3, 4, by a lute of Portland or other suitable cement.

The positive side of the circuit is connected to the bus bar 11 connecting the several anodes of anode member 7. The negative side of the circuit is led to the cathode member 6 through the bus bars 12, 12.

The upper ends of the opposite lateral portions of the casing 1 are made gas-tight by the cover members 13, 13, and the oppositely disposed inlet pipes 14, 15, are provided for the supply of steam or other suitable medium from a suitable source thereof. The flow of the steam or other medium is controlled by the valves 16. On the outer side of the cathode member 6 are arranged the oppositely disposed screens 17, 18, held in the angle plates 19, 19, and supported by the strips 20.

At the bottom of the cell proper 2 are provided the two strips 21 of curved asbestos or like material and properly positioned to catch the precipitated matter. When the precipitated matter has accumulated, the strips 21 may be taken out of the cell after the anode member 7 has been removed to permit access to the strips 21,

Instead of a number of strips 21, the precipitate collecting means may be formed of a single strip of asbestos or the like slightly bent at the side to form a pan-like structure.

The tilting pan 22 shown disposed below the cathode member 6 collects the concentrated caustic soda; the particular tilting pan 22 is shown pivoted at opposite pivots 23 insulated from casing 1 and other parts 24 of the cell; the pan 22 is operated to empty when the contents reach a predetermined amount. The caustic soda empties from the tilting pan 22 into the stationary pan 24 from which the caustic soda is discharged through the outlet 25.

Suitable provision is made for leading off the evolved hydrogen or other gas through the outlet pipes 26. Fig. 1 indicates an outlet pipe 26 on one side of the cell and a similar outlet pipe may be provided on the opposite side, the outlets for the hydrogen or other gas may be increased in number and disposed at suitable points.

As one method of carrying out my invention, assume that a practically saturated solution of sodium chlorid has been fed into the cell 2 through the inlet pipe 29 and the current properly regulated for the electrolysis of the above solution. The steam is supplied through the inlet pipes 14, 15 and regulated by cocks 16 to secure a "faint cloud" within the interior of the casing 1, and the current density is regulated to produce an amount of sodium commensurate with the amount of steam supplied to the interior sides of the cathode.

The condensed water or other liquid is caught within the trap 31 to thereby preclude presence of the same within the reaction area adjacent the cathode. Upon electrolysis, the sodium cathion encounters the steam within the perforations or reticula of the cathode member 6, or strictly, at the points of intersection of the inner end of the perforations or reticula of the cathode member 6 with the asbestos diaphragm 5, giving rise to the formation of caustic soda mixed more or less with sodium chlorid and the evolution of hydrogen. The chlorin evolved at the anode 7 is collected within the dome 9 and discharged through outlet 28. The main bulk of the formed caustic liquor containing caustic soda mixed more or less with sodium chlorid, trickles down the outer side of the cathode member 6 into the tilting pan 22. However, the bursting of the bubbles of hydrogen within the cathode member 6 "sputters" the caustic liquor which is caught by the screens 17, 18, and directed into the tilting pan 22.

After a predetermined amount of the caustic liquor is collected within the pan 22, the same is tilted by suitable rotating means to empty into the fixed pan 24, from which

the caustic liquor is discharged through outlet 25. Such liquid cathode member is then concentrated by heating whereby the sodium chlorid content is separated in the form of 5 crystals. The sodium chlorid thus separated is neutralized and again put in solution for reelectrolysis.

The mesh of the permeable screens 17, 18, is chosen to freely admit the steam there- 10 through, but to catch substantially all of the "sputtered" liquid or semi-liquid cathode product. The screens 17, 18, serve also to effect uniformity in the atmosphere of the steam supplied to the cathode reaction area.

15 In the event of the presence of condensed water or other liquid within the casing 1, as by cooling due to contact with the outer walls of the casing 1, such water or other moisture is collected at points remote from 20 the cathode reaction area, and discharged through the outlets 30.

If it is desired to use the circulating system for the steam or other medium, a pump or like circulating means may be connected 25 to the suitable outlets to return the discharged steam or like medium through the inlet pipes 15.

It will be noted that the presence of the steam within the container, usually at a 30 temperature not less than 97° C. maintains the electrolytic bath at the most efficient temperature of electrolysis and at the same time the steam or like medium is supplied to the cathion at the most efficient temperature 35 for reaction therewith and for securing high concentration of the liquid or semi-liquid reaction product. It will also be noted that the steam or like medium within the container acts as an electrically-insulating 40 blanket to preclude electric current losses. To this end, it is desirable to electrically insulate the pivots of the tilting pan 22 from the walls of the container 1 which usually are formed of iron or like material.

45 It will be seen that my method is applicable to other salts and compounds of sodium and other alkali metals, solutions of compounds of the alkali earth metals, etc.

Whereas I have described my method by 50 reference to a specific procedure, relative to specific chemical compounds, it will be understood that many changes and modifications may be made without departing from my invention.

55 What I claim and desire to secure by Letters Patent is:—

1. The method of electrolyzing solutions of salts of the alkali and alkali earth metals and like compounds, comprising subjecting the same to electrolysis, transferring the resulting cathion to a point out of contact with the electrolyzed solution while treat- 60 ing the cathion with a reacting medium in substantially solely vaporized condition.

65 2. The method of electrolyzing solutions

of salts of the alkali and alkali earth metals and like compounds, comprising subjecting the same to electrolysis, transferring the resulting cathion to a point out of contact with the electrolyzed solution while treat- 70 ing the cathion with a reacting medium in substantially solely vaporized condition and withdrawing the resulting liquid cathode product to a point electrically disconnected from the cathode. 75

3. The method of electrolyzing solutions of salts of the alkali and alkali earth metals and like compounds, comprising subjecting the same to electrolysis, transferring the resulting cathion to a point out of contact with the electrolyzed solution, treating the resulting cathion with a reacting me- 80 dium while precluding the condensation of the reacting medium within the reaction region and withdrawing the resulting liquid 85 cathode product to a point electrically disconnected from the electrolyzed solution.

4. The method of electrolyzing solutions of salts of the alkali and alkali earth metals and like compounds, comprising subjecting the same to electrolysis, transferring the resulting cathion to a point out of contact with the electrolyzed solution, treating the resulting cathion with a vaporized reacting medium while precluding the condensation 90 of the reacting medium within the reaction region and withdrawing the resulting liquid 95 cathode product by causing the same to fall by drops to a point electrically disconnect- 100 ed from the cathode.

5. The method of electrolyzing solutions of salts of the alkali and alkali earth metals and like compounds, comprising subjecting the same to electrolysis, transferring the resulting cathion to a point out of contact 105 with the electrolyzed solution, treating the resulting cathion with a vaporized reacting medium while precluding the condensation of the reacting medium within the reaction region and withdrawing the resulting liquid 110 cathode product in the form of drops and collecting the drops of liquid cathode product at a point electrically disconnected from the cathode.

6. The method of electrolyzing solutions 115 of salts of the alkali and alkali earth metals and like compounds, comprising subjecting the same to electrolysis by means of a cathode having only one face in contact with the electrolyzed solution, transferring the re- 120 sulting cathion to the opposite face of the cathode while supplying a vaporized re- acting medium to substantially the entire superficial area of said opposite face, and withdrawing the resulting liquid cathode 125 product to a point electrically disconnected from the cathode.

7. The method of electrolyzing solutions of salts of the alkali and alkali earth metals and like compounds, comprising subjecting 130

the same to electrolysis by means of a cathode having only one face in contact with the electrolyzed solution, transferring the resulting cathion to the opposite face of the cathode while supplying a vaporized reacting medium to substantially the entire superficial area of said opposite face, and withdrawing the resulting liquid cathode product in the form of drops to a point electrically disconnected from the cathode.

10. 8. The method of electrolyzing solutions of salts of the alkali and alkali earth metals and like compounds, comprising subjecting the same to electrolysis by means of a cathode having only one face in contact with the electrolyzed solution, transferring the resulting cathion to the opposite face of the cathode while supplying a vaporized reacting medium to substantially the entire superficial area of said opposite face, and withdrawing the resulting liquid cathode product by causing drops of the liquid cathode product to fall to a point electrically disconnected from the cathode.

25. 9. The method of electrolyzing solutions of salts of the alkali and alkali earth metals and like compounds, comprising subjecting the same to electrolysis by means of a cathode having only one face in contact with the electrolyzed solution, transferring the resulting cathion to the opposite face of the cathode, supplying a vaporized reacting medium to substantially the entire superficial area of said opposite face of the cathode while precluding condensation of the reacting medium within the reaction region and withdrawing the resulting liquid cathode product to a point electrically disconnected from the cathode.

30. 10. The method of electrolyzing solutions of salts of the alkali and alkali earth metals and like compounds, comprising the subjecting the same to electrolysis, transferring the resulting cathion to a point out of contact with the electrolyzed solution while treating the cathion with steam in substantially solely vaporized condition.

35. 11. The method of electrolyzing solutions of salts of the alkali and alkali earth metals and like compounds, comprising subjecting the same to electrolysis, transferring the re-

sulting cathion to a point out of contact with the electrolyzed solution while treating the cathion with steam in substantially solely vaporized condition and withdrawing the resulting liquid cathode product to a point electrically disconnected from the cathode.

40. 12. The method of electrolyzing solutions of salts of the alkali and alkali earth metals and like compounds, comprising subjecting the same to electrolysis, transferring the resulting cathion to a point out of contact with the electrolyzed solution, treating the resulting cathion with steam while precluding the condensation of the steam within the reaction region and withdrawing the resulting liquid cathode product to a point electrically disconnected from the electrolyzed solution.

45. 13. The method of electrolyzing solutions of salts of the alkali and alkali earth metals and like compounds, comprising subjecting the same to electrolysis by means of a cathode having only one face in contact with the electrolyzed solution, transferring the resulting cathion to the opposite face of the cathode, while supplying steam to substantially the entire superficial area of said opposite face and withdrawing the resulting liquid cathode product in the form of drops to a point electrically disconnected from the cathode.

50. 14. The method of electrolyzing solutions of salts of the alkali and alkali earth metals and like compounds, comprising subjecting the same to electrolysis by means of a cathode having only one face in contact with the electrolyzed solution, transferring the resulting cathion to the opposite face of the cathode, supplying steam to substantially the entire superficial area of said opposite face of the cathode while precluding condensation of the steam within the reaction region, and withdrawing the resulting liquid cathode product in the form of drops to a point electrically disconnected from the cathode.

55. In testimony whereof I have signed this specification in the presence of two subscribing witnesses.

HARRY R. NELSON.
